UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

THREAD-CUTTER FOR LOOMS.

1,366,949.

Specification of Letters Patent.

Patented Feb. 1, 1921.

Application filed December 12, 1918. Serial No. 266,387.

To all whom it may concern:

Be it known that I, EPPA H. RYON, a citizen of the United States, residing at Waltham, in the county of Middlesex and State of Massachusetts, have invented a new and useful Thread-Cutter for Looms, of which the following is a specification.

This invention relates to a thread cutter for looms particularly adapted for use in connection with automatic weft replenishing mechanism.

It is the general object of my invention to provide an improved construction of thread cutter by which this operation may be performed with accuracy and efficiency.

With this general object in view, an important feature of my invention relates to the provision of a thread cutter normally held inoperative but releasable by the downward movement of the incoming weft carrier upon the occurrence of transfer. Another and very important feature of my invention relates to the provision of a thread cutter which is held inoperative when engaged by the lay and which performs its cutting operation as the lay moves backward away from the fell of the cloth.

Further features of my invention relate to the provision of resetting devices preferably associated with the transferring mechanism, to the provision of a novel and efficient cutter, and to other arrangements and combinations of parts hereinafter described and more particularly pointed out in the appended claims.

A preferred form of my invention is shown in the drawings, in which—

Figure 1 is a plan view of my improved thread cutter;

Fig. 2 is a side elevation thereof;

Fig. 3 is a partial sectional elevation taken along the line 3—3 in Fig. 1;

Fig. 4 is a view similar to Fig. 3, but showing the parts in a different position, and

Fig. 5 is a side elevation of a portion of the weft carrier magazine and the mechanism for releasing the thread cutter.

In its preferred form, my improved thread cutter is mounted upon and forms a part of the temple adjacent the weft carrier magazine. In Fig. 1 I have shown a temple 10 mounted upon a slide 11 movable in a guide 12 adjustably secured to a stand 13 which in turn is fixed to the breast beam

14. These parts are of the usual type and the slide 11 is normally forced yieldingly rearward or toward the lay 15. A pocket or recess 16 is formed in the head of the slide 11, as shown in Figs. 3 and 4, and cutters 17 and 18 are slidably mounted therein. The cutter 17 is provided with slots 19 and 20 through which extend pins 21 and 22 fixed in the slide 11.

The cutter 18 is pivoted at 23 to the cutter 17 and is provided with an inclined cam slot 24 through which extends the pin 22. A lug 25 extends laterally from a depending portion 17^a of the cutter 17 and is engaged by the lower end of a spring 26 mounted on a stud 27 fixed in the slide 11, the upper end of the spring engaging a shoulder 28 on the slide. When the cutters 17 and 18 are free to move, the spring 26 gives the cutter 17 a straight-line rearward movement, and at the same time the cam slot 24 in the cutter 18 causes this cutter to receive an angular cutting movement about its pivot 23.

A locking lever 29 is pivoted at 30 to the slide 11 and extends forward therefrom. This lever is provided with a shoulder 31 adapted to engage the lug 25 on the cutter 17 and to lock the cutters in their extreme forward or open position as shown in Figs. 2 and 3. The forwardly extending portion of the lever 29 is provided with a stud 32 positioned for engagement by an arm 33 fixed to a horizontal shaft 34. A spring 35 is connected at one end to the stud 27 on the slide 11 and at the other end to an upward extension 36 on the arm 29, the spring tending to move the lever into locking position. The downward extension 17^a of the cutter 17 is engaged by the lay 15 as the latter moves forward and is moved thereby beyond the shoulder 31 of the lever 29, which immediately drops to locking position after the lug 25 has moved forward from beneath the shoulder.

The mechanism for releasing the cutter is shown in Fig. 5, in which I have shown portions of a weft carrier magazine 40 on which a transerrer 41 is pivoted at 42. The details of the magazine form no part of my present invention and are not shown herein, but may be of the general type shown in my copending application Serial No. 244,637, filed July 12, 1918. For the purposes of this application it is merely necessary to

state that the weft carriers are released after indication and move downward between the fixed guide 43 and the yielding guide 44 to the position indicated at W in Fig. 5. Upon the next downward movement of the transferrer the fresh weft carrier is forced downward into the shuttle, and the exhausted weft carrier is simultaneously ejected therefrom.

10 As the incoming weft carrier moves downward, the butt of the carrier engages a rod 45 slidable in bearings 46 and 47 on the magazine 40, the rod being moved forwardly or to the left in the drawing as the weft carrier descends. The front end of the rod engages a screw 48 threaded into a projection on a latch 49 pivoted at 50 to the magazine 40. The screw 48 forms in effect an adjustable shoulder on the latch 49 for engagement by the rod 45. At its lower end the latch is provided with a hook 51 which engages an arm 52 on the outer end of the shaft 34 previously described. A spring 53 holds the adjusting screw 48 against the end of the rod 45 and rearward movement of the rod is limited by a collar 54 which engages the rod bearing 47.

15 The transferrer is operated by a rod 55 which is reciprocated vertically by a cam on the loom cam shaft once in every two picks of the loom. The rod 55 carries a resetting arm 56 which engages the arm 52 on the shaft 34 and raises the same above the hook 51 after the thread-cutting operation.

20 I will now briefly describe the general operation of my invention. As the weft carrier W is fed to the shuttle by the transferrer 41, the butt of the weft carrier forces the sliding rod 45 to the left in Fig. 5 and disengages the hook 51 from the arm 52. At the same time the resetting arm 56 is in lowered position so that the shaft 34 is free to turn under the influence of a spring 57 (Fig. 1) thereon. As the arm 52 moves downward the arm 33 (Fig. 2) on the shaft 34 moves upward, engaging the stud 32 and lifting the lever 29 to release the cutters, the spring 57 being of sufficient strength to overcome the spring 35. The parts are so timed that the downward extension 17^a of the cutter 17 will be engaged by the lay 37 when the cutters are released, and no cutting action will therefore occur until the lay has moved back a certain distance from the fell of the cloth. As the lay moves rearward and releases the extension 17^a of the cutter 17, the cutters 17 and 18 are also moved rearwardly by the spring 26, such movement causing the cutters to move relatively from the position shown in Fig. 3 to that shown in Fig. 4, severing any weft thread extending between the cutters. The

weft thread has been previously positioned for engagement by the cutters by the forward movement of the reed R as the lay 65 beats up.

Having thus described my invention, certain novel features thereof will be evident. Attention is called to the fact that the operation of the thread cutter, as herein shown, is controlled directly by the incoming weft carrier and that the thread-cutting operation occurs after the lay has passed its front center. My improved thread cutter is also applicable to a loom in which the transferrer is actuated only after indication of transfer, and in such looms the thread cutter may be released by the movement of any part associated with the transferrer.

25 My improved thread cutter is of particular value in any loom in which the transfer occurs upon the same pick as the indication by the weft detecting mechanism, as its cutting operation occurs much later than that of other cutters in common use.

30 While I have shown my invention as developed in a thread cutter, certain features of the actuating mechanism are capable of more general application to other devices for acting upon the weft after a weft carrier is transferred. It will be also evident that changes and modifications can be made in my invention as shown herein, by those skilled in the art, without departing from the spirit and scope thereof as set forth in 95 the claims, and I do not wish to be otherwise limited to the details herein disclosed, but what I claim is—

35 1. In a loom, a thread cutter, means to hold said cutter normally inoperative, releasing mechanism therefor operable by engagement by the incoming weft carrier during transfer, and actuating means for said cutter.

40 2. In a loom having a weft carrier transferrer, in combination, a thread-cutter, a detent effective to hold said cutter normally inoperative, means operative during downward movement of said transferrer to withdraw said detent and release said cutter, 110 actuating means for said cutter, and means operated by said transferrer during upward movement thereof, effective to reset said detent.

45 3. In a loom, a thread cutter, means to hold said cutter inoperative, and releasing devices therefor controlled by a member interposed in the path of the incoming weft carrier and actuated thereby to release said thread cutter.

50 In testimony whereof I have hereunto affixed my signature.

EPPA H. RYON
